(57) **CLAIM**

The ornamental design for a tissue clamping member, as shown and described.

DESCRIPTION

FIG. 1 is a top perspective view of a tissue clamping member showing our new design;

FIG. 2 is a right side view thereof, the left side view being a mirror image of the right side view;

FIG. 3 is a front view thereof;

FIG. 4 is a rear view thereof;

FIG. 5 is a top plan view thereof; and,

FIG. 6 is a bottom plan view thereof.

The broken lines in the drawings are for illustrative purposes only and form no part of the claimed design.
